UNITED STATES PATENT OFFICE.

GEORGE FRANCIS MCINTOSH, OF GARDINER, MAINE.

CURLING-IRON HOLDER.

SPECIFICATION forming part of Letters Patent No. 478,123, dated July 5, 1892.

Application filed August 5, 1891. Serial No. 401,786. (No model.)

To all whom it may concern:

Be it known that I, GEORGE FRANCIS MCINTOSH, a citizen of the United States, residing at Gardiner, in the county of Kennebec and 5 State of Maine, have invented a new and useful Curling-Iron Holder, of which the following is a specification.

This invention relates to a device for holding curling-irons while being heated; and the 10 objects in view are to provide a cheap and simple device for the above purpose, which is adapted to be applied to an ordinary lamp-chimney and to support in proper position for heating an ordinary curling-iron.

15 Other objects and advantages of the invention will appear in the following description and the novel features thereof will be particularly pointed out in the claims.

Referring to the drawings, Figure 1 is a perspective of a curling-iron holder constructed 20 in accordance with my invention, the same being in position upon a lamp-chimney and supporting a curling-iron. Fig. 2 is an enlarged detail in perspective of the holder.

25 Like numerals of reference indicate parts in both the figures of the drawings.

In practicing my invention I cut from sheet metal an oblong blank, which constitutes the frame 1, and stamp upon the same 30 from a point near its center to near its lower end a longitudinal tongue 2, which tongue is outwardly bent away from the frame and near its lower extremity is inwardly bent in contact with the frame, so that the tongue as 35 a whole is compoundly curved. Above the tongue 2 there is cut from the blank and disposed in a direction opposite to the tongue 2 a rearwardly-inclined tongue 3, the same being concaved in cross-section, as shown, and 40 disposed at an angle of about forth-five degrees with relation to the frame 1. The removal of the tongue 3 forms an opening 4 in the frame at the base of the tongue.

45 8 designates an ordinary lamp-chimney mounted upon a lamp 6, and over the upper edge of said chimney the spring-tongue 2 is sprung, said tongue passing upon the inside of the chimney, while the lower end of the frame 1 rests upon the outside thereof, said 50 chimney thus being embraced by the tongue and frame, whereby the device is supported

upon the chimney. When in this position, the tongue 3, which, as before stated, is inclined, will extend outwardly from the upper end of the chimney, and by introducing an ordinary curling-iron 7 through the opening 4 and resting the same upon the tongue 3 said iron will be supported and its inner end held in the path of the flame from the burner of the lamp. When thus supported, the iron 60 will be quickly heated, for, as is well known, the heat rising through lamp-chimneys is very intense, and said heating will be accomplished not only with dispatch, but without the necessity of supporting the iron by hand 65 or without any attention whatever upon the part of the user, except to remove the iron when sufficiently hot.

It will be seen that the iron may be readily introduced and removed without any chance 70 whatever of burning the hands. If it is desired to simply heat the extreme end of the iron, the same need not be inserted so far into the flame, and if, on the other hand, the entire curling portion of the iron is to be heated 75 the device is inserted the full distance, and in either instance the heating is accomplished with the same facility and dispatch.

It will be seen that the device heretofore described may be easily and cheaply struck 80 up from spring sheet metal and sold at a slight cost.

The contracted part 5 of the holder subserves an important function. It prevents the curling-iron from tilting off of the support 85 when it is drawn back.

Having described my invention, what I claim is—

1. The herein-described curling-iron holder, the same consisting of a frame formed of 90 sheet metal and having a tongue struck therefrom near its lower end, said tongue and frame being adapted to embrace a lamp-chimney, and the frame provided near its upper end with an inclined iron-supporting tongue, 95 substantially as specified.

2. The herein-described curling-iron holder, the same consisting of an oblong sheet-metal frame having an upper and a lower tongue struck therefrom at contrary sides of the 100 frame, the lower tongue being compoundly curved and the upper tongue being inclined

and transversely curved, substantially as specified.

3. The herein-described curling-iron holder, the same consisting of an oblong sheet-metal frame having an upper and a lower tongue struck therefrom at contrary sides of the frame, the lower tongue being compoundly curved and the upper tongue being inclined and transversely curved, said frame having a contracted opening above its upper tongue

adapted to fit the iron, substantially as specified.

In testimony that I claim the foregoing as my own I have hereto affixed my signature in presence of two witnesses.

GEORGE FRANCIS McINTOSH.
